US0D1061305S

(12) **United States Design Patent** (10) Patent No.: **US D1,061,305 S**
(45) Date of Patent: ** Feb. 11, 2025

(54) **NECKLACE**

(71) Applicant: **Yiwu Ouye Network Technology Co., Ltd.**, Zhejiang (CN)

(72) Inventor: **Wenjuan Tong**, Zhejiang (CN)

(**) Term: **15 Years**

(21) Appl. No.: **29/960,981**

(22) Filed: **Sep. 3, 2024**

(51) LOC (15) Cl. **11-01**

(52) U.S. Cl.

USPC **D11/7**

(58) **Field of Classification Search**

USPC D11/1-18

CPC A44C 15/00; A44C 15/005

See application file for complete search history.
